DOUBLE FOCUS X-RAY TUBE

Otto William Langhans, Bloomfield, N. J., assignor, by mesne assignments, to Westinghouse Electric and Manufacturing Company, East Pittsburgh, Pa., a corporation of Pennsylvania

Application August 24, 1935, Serial No. 37,697

6 Claims. (Cl. 250—35)

My invention relates to X-ray apparatus and particularly to such apparatus employing an X-ray tube known to the art as the double focus type.

5 X-ray tubes of this general type are known to the art for producing focal spots of different area which are utilized by the Roentgenologist for diagnostic purposes. For example, in the making of fluoroscopic examinations a focal spot of 10 small area is employed for the purpose of producing as much detail as possible in the resulting image portrayed upon the fluorescent screen. Accordingly the area of the tungsten target impinged by the electrons coming from the thermionic cathode is comparatively small with the 15 result that the generated X-rays are confined to a small area.

In the making of radiographic exposures a larger focal spot is produced on the surface of 20 the anode with a resultant increase in the area of the emitted X-ray beam. This necessity for the production of different focal spots accordingly requires the employment of separate X-ray tubes or a single tube capable of producing a 25 large and small focal area by the utilization of cathodes of different size. Moreover, some provision must be made to energize the desired cathode which gives the appropriate focal spot so that no possibility of error occurs on the part of 30 the operator.

It is accordingly an object of my present invention to provide an X-ray apparatus wherein a double focus X-ray tube is employed having different size cathodes which may be alternately 35 energized at will by the operator.

Another object of my present invention is the provision of an X-ray apparatus wherein an X-ray opaque casing surrounds an X-ray tube of the double focus type having thermionic cathodes of different size and one of the cathodes is 40 energized at a time so as to produce a desired focal spot upon rotation of the X-ray tube in its casing.

Another object of my present invention is the provision of an X-ray apparatus employing an X-ray tube of the double focus type wherein the tube is rotatably supported within an X-ray opaque casing and upon rotation of the tube to various positions its respective thermionic cathodes are energized so as to produce a focal spot of the desired area as well as a visual indication being given to the operator of the comparative size of the focal area produced by the particular selected cathode.

55 Still further objects of my present invention will become obvious to those skilled in the art by reference to the accompanying drawings wherein:

60 Figure 1 is a side view of an X-ray apparatus

constructed in accordance with my present invention.

Fig. 2 is a sectional view on enlarged scale of the apparatus as shown in Fig. 1.

Fig. 3 is a sectional view taken on the line 5 III—III of Fig. 2.

Fig. 4 is an end view of the anode of the X-ray tube taken on the line IV—IV of Fig. 2 and looking in the direction indicated by the arrows, and

Fig. 5 is an end view of the cathode electrode 10 of the X-ray tube taken on the line V—V of Fig. 2 and looking in the direction indicated by the arrows.

Referring now to the drawings in detail I have shown in the several figures an X-ray opaque 15 shield or casing 5 which may be of lead glass or a phenolic condensation product impregnated with a high atomic weight material or having a lining of such material as lead or the like. This casing 5 may be formed of two bell shaped members 20 suitably joined together, as by means of cap screws 6, and formed with an opening constituting a window 7 pervious to X-rays. A cone 8 may be arranged to engage the casing 5 in any suitable manner and serves the purpose of directing the X-rays emerging from the X-ray tube through the pervious window 7. One end of the casing 5 is closed and co-axially disposed relative to the longitudinal axis of the casing is an electrical terminal 9 having a spring contact 25 member 10. A similar terminal 12 is also provided in the closed end of the casing which is disposed adjacent the perimeter of the latter. These terminals 9 and 12 are adapted to be engaged by electrical conductors 13 and 14 extending from a suitable source of low tension heating current as well as one of these conductors supplying one side of high voltage potential for the 30 energization of an X-ray tube.

The cable containing the conductors 13 and 14 40 passes through an insulated cap 15 which threadedly engages the closed end of the casing 5 thus forming a shield for the exposed ends of these terminals. An X-ray tube 16 is rotatably mounted within the casing 5 which tube is of the 45 double focus type being provided with a thermionic cathode 17 and a similar cathode 18, the latter of which is, as shown, of smaller area than the cathode 17. Both these thermionic cathodes are recessed within a suitable metallic member 50 19 which forms focusing cups for the respective thermionic cathodes.

A plurality of leading-in conductors pass through the usual press portion 20 of the X-ray tube and one of these leading-in conductors 22 55 is connected to one end of each of the thermionic cathodes 17 and 18 as well as to the member 19, while the leading-in conductor 23 is connected to the remaining end of the smaller thermionic cathode 18. Similarly the leading-in conductor 24 60

is connected to the remaining end of the larger thermionic cathode 17 and these latter leading-in conductors 23 and 24 are suitably insulated from the metallic member 19 by extending through 5 enlarged openings 25 provided therein.

The cathode end of the X-ray tube is provided with a base 26 of suitable insulating material having a plurality of contact members 27, 28 and 29 embedded therein. The contact member 28 is 10 co-axially disposed relative to the longitudinal axis of the X-ray tube and is connected to the leading-in conductor 22 and thus to one end of both the thermionic cathodes 17 and 18. In a similar manner the contact terminals 27 and 29 15 which are disposed adjacent the periphery of the base member 26 are connected to the remaining leading-in conductors 23 and 24 and thus to the remaining ends of the respective cathodes 17 and 18. The spacing between the centrally disposed 20 contact terminal 28 and the outer contact terminals 27 and 29 is similar to that between the contact terminals 9 and 12 of the casing so that contact is established between the contact terminals 9 and 28 at all times when the X-ray tube 25 is positioned within the casing and the casing contact terminal 12 establishes engagement with either of the contact terminals 27 and 29 of the X-ray tube as hereinafter more fully explained.

The base 26 is provided with a peripheral groove 30 which extends approximately 180° around the base and a suitable set screw or the like 32 is provided in the casing 5 which extends into the peripheral groove 30 so as to limit rotation of the X-ray tube to 180°. The anode electrode 33 of 35 the X-ray tube is formed of a good heat conducting material, such as copper, and embedded in the surface thereof adjacent the thermionic cathodes is a pair of angularly disposed targets 34 and 35 formed of suitable refractory material, such 40 as tungsten. The larger target 34 is disposed opposite the larger area thermionic cathode 17 so as to be impinged by the electrons flowing from the latter upon energization thereof, and similarly the smaller area target 35 is disposed opposite to the thermionic cathode 18 for the same purpose.

The anode 33 is provided with a stem 36 of the same material as the anode itself which extends exteriorly of the casing 5 through an open end 50 thereof and is provided with a cooling radiator 37 for the purpose of dissipating the heat generated at the anode due to the impact of the electrons during operation of the tube. To assist in rotating the tube a member 38 may be provided constituting a wing nut or the like so as to be readily gripped by the operator for the purpose of rotating the tube. The base 26 provided on the cathode of the X-ray tube frictionally engages the casing 5 and thus forms a bearing for this end of 60 the tube while the anode end may be supported by a collar or the like 39 formed of cork or other suitable material constituting a bearing for the anode end of the X-ray tube.

A window 40 is also provided in the casing 5 65 which window registers with indicia provided on the base 26 so that as the tube is rotated from one position to another the lettering of "large" or "small" corresponding to the particular thermionic cathode energized from the cathode heating source will be indicated. Due to the tube terminal 28, as before stated, always remaining in contact with the casing terminal 9 and particularly the spring clip 10, when the tube is in the position shown in Fig. 2, the tube terminal 29 70 will establish engagement with the casing ter-

5 minal 12 so that the smaller thermionic cathode 18 receives heating current through the conductors 13 and 14 as well as the leading-in conductors 22 and 24. At the same time the smaller area tungsten target 35 aligns with the X-ray 10 pervious window 7 and the electrons impinging on the anode target 35 causes the generation of X-rays which emerge through the pervious window 7. The indicium "small" will also register with the opening or window 40 in this position of the tube to thus indicate to the operator that the smaller thermionic cathode is energized and that a corresponding small area focal spot is being produced by the X-rays flowing through the window 7 from the target 35.

15 When it is desired that the X-ray tube be employed for diagnostic purposes requiring a larger focal area the operator need only rotate the X-ray tube 180° by gripping the member 38. Such rotation causes a disengagement of the casing 20 terminal 12 and the tube terminal 29 and an engagement of the terminal 27 with the terminal 12. This accordingly enables the larger thermionic cathode 17 to be energized from the cathode heating source to which the conductors 13 and 25 14 are connected.

Simultaneously the larger area anode target 34 is rotated to a position where the same aligns with the X-ray pervious window 7 so that the X-rays generated by impact of the electrons flowing 30 from the larger area thermionic cathode 17 emerge from the tube and casing through the window 7 in the same manner as previously described.

Again the indicium "large" inscribed or stenciled upon the base member 26 will register with the window 40 and the indicium "small" will be moved away from this window thus apprising the operator that the larger area thermionic cathode is now energized with the resulting production of a larger focal spot. Moreover the peripheral groove 30 into which the set screw 32 extends so limits rotation of the tube that one or the other of the tube terminals 27 or 29 always engages the casing terminal 12, and as the terminal 28 remains in fixed engagement with the terminal 9 one or the other of the thermionic cathodes is energized and at the same time one or the other of the anode targets aligns with the X-ray pervious window.

50 It thus becomes obvious to those skilled in the art that I have provided an X-ray apparatus employing an X-ray tube of the double focus type wherein the X-ray tube is rotatably supported within an X-ray opaque casing and upon 55 rotation of the tube to various positions one or the other of the thermionic cathodes will be alternately energized. Simultaneously with rotation of the tube one or the other of the anode targets aligns with the X-ray pervious window 60 provided in the casing so that the generated X-rays produce the requisite focal area or spot required for the particular diagnostic examination. Furthermore, a visual indication is given to the operator apprising him of the relative 65 size of the focal spot generated upon energization of either of the thermionic cathodes at any given period.

70 Although I have shown and described one specific embodiment of my invention I do not desire to be limited thereto as various other modifications of the same may be made without departing from the spirit and scope of the appended claims.

What is claimed:

1. An X-ray apparatus comprising an X-ray opaque casing having an X-ray pervious window therein for the emergence of X-rays, an X-ray tube rotatably supported within said casing and provided with an anode having a plurality of targets and a plurality of thermionic cathodes of different size for producing dissimilar focal areas upon the respective targets, means disposed 5 exteriorly of said X-ray tube and connected to said thermionic cathodes, and means carried by said casing connected to a suitable source of heating current and alternately engageable by portions of said first mentioned means to cause 10 energization of one of said thermionic cathodes at a time upon rotation of said X-ray tube to align either of said anode targets with said X-ray pervious window.
2. An X-ray apparatus comprising an X-ray opaque casing having an X-ray pervious window therein for the emergence of X-rays, an X-ray tube rotatably supported within said casing and provided with an anode having a plurality of targets and a plurality of thermionic cathodes 15 of different size for producing dissimilar focal areas upon the respective targets, means disposed exteriorly of said X-ray tube and connected to said thermionic cathodes, means carried by said casing connected to a suitable source of heating current and alternately engageable by portions of said first mentioned means to cause 20 energization of one of said thermionic cathodes at a time upon rotation of said X-ray tube to align either of said anode targets with said X-ray pervious window and one 25 of said thermionic cathodes is energized at a time.
3. An X-ray apparatus comprising an X-ray opaque casing having an X-ray pervious window therein for the emergence of X-rays, an X-ray tube rotatably supported within said casing and provided with an anode having a plurality of targets and a plurality of thermionic cathodes 30 of different size for producing dissimilar focal areas upon the respective targets, means disposed exteriorly of said X-ray tube and connected to said thermionic cathodes, means carried by said casing connected to a suitable source of heating current and alternately engageable by portions of said first mentioned means to 35 cause energization of one of said thermionic cathodes at a time upon rotation of said X-ray tube to align either of said anode targets with said X-ray pervious window, and indicia carried by said first mentioned means and registering 40 with an opening provided in said casing to indicate the relative size of the focal area produced by the particular cathode which is connected to said last mentioned means by rotation of said X-ray tube. 45
4. An X-ray apparatus comprising an X-ray opaque casing having an X-ray pervious window therein for the emergence of X-rays, an X-ray tube rotatably supported within said casing and provided with an anode having a plurality of targets and a plurality of thermionic cathodes of different size adapted to 50 be independently heated for producing focal spots of different areas upon the respective targets, means disposed exteriorly of said X-ray tube and connected to said thermionic cathodes with a portion of said means being engageable with said first mentioned means for energizing one 55 of said thermionic cathodes upon rotation of said X-ray tube to one position, and said portion of said last mentioned means being disengaged from said first mentioned means and the remaining portion thereof engaging said first 60 mentioned means upon rotation of said X-ray tube to another position, and means carried by said casing and cooperating with said X-ray tube to limit rotation of said tube in order that only one of said anode targets is aligned with said pervious window and one of said thermionic cathodes is energized at a time. 65
5. An X-ray apparatus comprising an X-ray opaque casing having an X-ray pervious window therein for the emergence of X-rays, an X-ray tube supported by said casing for rotation therein and provided with an anode having a plurality of angularly disposed targets and a plurality of thermionic cathodes of different size adapted to 70 be independently heated for producing focal spots of different areas upon the respective targets, a base carried by one end of said tube provided with a plurality of contact terminals connected to said thermionic cathodes, a pair of contact terminals carried by said casing and connected to a suitable source of heating current and engageable by at least two of the contact terminals carried by said base for energizing one of said thermionic cathodes upon rotation of said X-ray tube to one position, and one contact terminal of said pair being disengaged from one contact terminal of said base and engageable with another contact terminal of said base upon 75 rotation of said X-ray tube to another position, and means carried by said casing and cooperating with said tube to limit rotation of said tube in order that only one of said anode targets is aligned with said pervious window and one of said thermionic cathodes is energized at a time. 80
6. An X-ray apparatus comprising an X-ray opaque casing having an X-ray pervious window therein for the emergence of X-rays, an X-ray tube rotatably supported within said casing and provided with an anode having a plurality of targets and a plurality of thermionic cathodes of different size for producing dissimilar focal areas upon the respective targets, means disposed exteriorly of said X-ray tube and connected to said thermionic cathodes, means carried by said casing connected to a suitable source of heating current and alternately engageable by portions of said first mentioned means to 85 cause energization of one of said thermionic cathodes at a time upon rotation of said X-ray tube to align either of said anode targets with said X-ray pervious window, and indicia carried by said first mentioned means and registering with an opening provided in said casing to indicate the relative size of the focal area produced by the particular cathode which is connected to said last mentioned means by rotation of said X-ray tube. 90
